1.12 : Perspective view 6

The broken lines depict portions of the refrigerator that form
no part of the claimed design; the dash-dot broken lines
define the boundary of the claimed design and form no part
thereof; reproduction 1.1 is a top right perspective view of
the refrigerator; reproduction 1.2 is a top left perspective
view thereof; reproduction 1.3 is a bottom right perspective
view thereof; reproduction 1.4 is a bottom left perspective
view thereof; reproductions 1.5 to 1.10 are the front, back,
left, right, top and bottom views thereof; reproduction 1.11
is a perspective view showing the handle at the lower part of

(Continued)

the refrigerator by removing the upper part of the refrigerator; reproduction 1.12 is a perspective view showing the handle at the upper part of the refrigerator by removing the lower part of the refrigerator; this design is for refrigerator having recessed shape handles, and the inside of the handle at the lower part is transparent.
